Primary Examiner — Brian N Vinson(74) *Attorney, Agent, or Firm* — John Brooks Law LLC;
John J Brooks, III(57) **CLAIM**

The ornamental design for a sheet dispensing assembly, as shown and described.

DESCRIPTION

FIG. 1 is a top perspective view of a sheet dispensing assembly showing the new design;

FIG. 2 is a left-side view thereof;

FIG. 3 is a right-side view thereof;

FIG. 4 is a front view thereof and the back view is a mirror image of the front view;

FIG. 5 is a top view thereof; and,

FIG. 6 is a bottom view thereof.

The broken lines are shown in the views for illustrative purposes only and form no part of the claimed design.
